E. STARBUCK

DANCING FIGURE

Filed May 20, 1921

E. Starbuck,

L. M. Thurlow

Attorney

UNITED STATES PATENT OFFICE.

ERNEST STARBUCK, OF PEORIA, ILLINOIS.

DANCING FIGURE.

Application filed May 20, 1921. Serial No. 471,266.

To all whom it may concern:

Be it known that I, ERNEST STARBUCK, a citizen of the United States, residing at Peoria, in the county of Peoria and State of Illinois, have invented certain new and useful Improvements in Dancing Figures; and I do hereby declare that the following is a full, clear, and exact description of the invention, which will enable others skilled in the art to which it appertains to make and use the same.

This invention pertains to toys. It has especial reference, however, to a toy having the form of a human figure adapted to 15 dance.

An object of the invention is to provide a dancing figure that will move about upon the floor without support other than the two feet thereof and wherein first one leg 20 and then the other will be operated, and in which also both legs will operate to the end that the movements and actions of a dancer will be very closely imitated.

Another object is to provide mechanism 25 in a dancing figure so organized and operated that independently mounted legs that support the figure will be both independently operated to produce certain desired results and operated simultaneously to affect 30 other actions.

Still another object is to so organize the driving mechanism of a dancing figure that its parts which control the legs upon which the figure is supported will operate said legs 35 in a variety of ways so that said figure will perform an infinite number of surprising unexpected movements in no set time or order.

Another object is to provide mechanism 40 in a dancing figure that will include a "change-gear" whereby one of the independently mounted legs of said figure will be set in motion, then both said legs, followed by the cessation of movement of the 45 leg first placed in action and the movement of the other.

Another object is the provision of mechanism by which the arms of the dancing figure will be separately and alternately raised 50 and lowered in accord with a change in the

leg movement, all of which will be pointed out herein aided by the appended drawing wherein:

Figure 1 is a type of figure with which the invention may be used. 55

Figure 2 is a side elevation of the operating mechanism employed within the figure.

Figure 3 is a front elevation of the same with parts broken away to better show the 60 structure.

Figure 4 shows, in perspective, a cam wheel or plate.

Figure 5 is a plan of the structure shown in Figures 2 and 3.

Figure 6 is an enlarged detail of a gear 65 shift mechanism as seen in Figure 2, and

Figure 7 is a transverse section of parts shown in Figure 6 taken on dotted line 7—7 of that figure.

1 and 2 designate a front and rear plate 70 respectively, of a housing or framing for the mechanism about to be described, which when completed for use may be dressed to represent a human figure; see Figure 1, for example. 75

3 is a shaft journaled in the plates 1 and 2 in customary manner upon which is mounted a spring 4, a driving gear 5 and a cam wheel or plate 6, all placed in the order named, the gear and cam wheel being affixed 80 to said shaft 3.

The said spring has control of the shaft in any usual well known way, power being stored through the use of the key 7.

8 is a shaft likewise journaled in the plates 85 1 and 2, beneath the parts named, and carries near each end adjacent the said plates, gears 9 and 10 each of which includes a sleeve portion 11 fixed with respect thereto terminating each in a series of teeth 12 facing in the direction of one another. 90

The gears 9 and 10 and their sleeves are mounted on the shaft in a manner to rotate with respect to that member.

Between the sleeves described is a pinion 95 13 to mesh with the gear 5 described, and adjacent it is a grooved member 14 in which the edge of the cam wheel 6 is adapted to lie. At the other side of the member 14, or that opposite the pinion, is a series of teeth 100

15 adapted to mesh with the teeth 12 of the gear 10.

Likewise, said pinion 13 has a series of similar teeth 16 adapted to mesh with the 5 teeth 12 of the gear 9.

The pinion, the member 14, and two series of teeth 15, 16 operate as a unit and the whole is adapted to shift bodily along the shaft 8 but is adapted to rotate the latter 10 through the use of a suitable key 17, for example, Figure 7.

Affixed to said shaft 8 is a scape wheel 17', while 18 is a pallet pivotally mounted on the plate 1, for example, and 19 is a 15 weight controlling it, the whole constituting a governor. However, other governing means may be employed since it is unimportant as to the method used.

The cam wheel has the form shown clearly in Figures 2 and 4. It consists of a circular plate or disc bent so as to have an angular middle portion through which the shaft 3 extends, opposite zones lying perpendicular to the axis of the shaft but spaced in different planes so that in its rotation, it takes the two positions shown in Figure 2. Since the opposite zones takes opposite positions in each revolution, the teeth 15, 16 will be alternately meshed with the teeth 12 of the gears 9, 10 as will more fully appear later.

20, 21 represent a pair of cranked shafts journaled in the plates 1 and 2. These lie at opposite sides of the gears 9, 10. One of 25 said shafts has a pinion 22 to mesh with the gear 9 and the other has a pinion 23 to mesh with the gear 10, Figure 5.

24 and 25 are two members representing the legs of the figure. These are pivotally 40 attached to the frame at their inner sides at the top by means of ears 26, for example, hung on rods 27 extending between the plates 1 and 2.

Pivoted to the outer sides of each of 45 the legs is a connecting rod 28 which engages the cranks of the shafts 20, 21, as shown.

29 indicates the arms of the figure which are pivoted to portion 29' extending between the plates 1 and 2.

30 indicates a rod mounted in the said plates and slideable in the direction of its length. The ends of the rod abut against the inner sides of the arms as shown in Figure 3.

31 is a bracket extending from the plate 1, for example, in position to overhang the cam wheel 6. Pivoted to it is a bell-crank 32, one end of which has two depending pins 33 to engage opposite sides of the said cam-wheel. The other end of the bell-crank has a pin 34 extending through a slot 35 in the rod 30.

The dress-skirt of the figure shown is 65 attached to the hands and during the dance-

ing, one of the arms is raised while the other is lowered, and in this movement, the dress-skirt is lifted first at one side and then at the other.

In the operation of the mechanism, the 70 power gear 5 imparts rotation to the pinion 13 and, as illustrated in Figure 2, the teeth 12, 16 are in mesh. The gear 9 will therefore be driven which in turn imparts rotation to the pinion 22. The movement 75 rotates the shaft carrying said pinion and imparts a vibratory movement to the leg at the left of Figure 3. As the power gear 5 continues to rotate, the cam wheel 6 will turn to a position where the cam portion 80 thereof will shift the grooved member 14 toward the right, Figure 6, to cause the meshing of the teeth 12, 15 and unmeshing of the teeth 12, 16, the gear 10 then taking up rotation and through the pinion 23 vibrating the leg at the right of said Figure 3.

In this connection a result is obtained which is believed to be entirely new and novel. It is to be noted in Figure 2 that the teeth 12, 16 are in mesh, the teeth 12, 15 being disengaged, the left leg only being in movement. Now as the cam wheel shifts, the member 14, as explained, both series of teeth 12, 16 and 12, 15 will have 95 engagement, both legs then being in movement until the said teeth 12, 15 finally having full mesh, the teeth 12, 16 will be disengaged. This peculiar relation of the parts thus produces an action of one leg 100 alone, then both legs, followed by the action of the opposite leg alone. The action of but one leg causes the figure to shift sidewise in one direction only. Then as 105 both legs are placed in operation, the figure will move sidewise in one direction or the other depending upon which foot may happen to support most of the weight and therefore creates the most friction upon the supporting surface.

Then as the other leg is finally independently vibrated by the release of the first, the figure will move in an opposite direction from that first taken. Since the crank-shafts are thus independently rotated and 115 are independent of one another, either may take up its motion. Although the cam-wheel has a continuous, and albeit, a steady rate of rotation due to the escape mechanism described, the said crank-shafts being placed 120 in operation and released at various chance positions, the resultant movements of the figure are infinite and unexpected, whereas, if the said shafts were intermittently operated while directly related, the results would 125 be but those expected in a continuous cycle. The very unexpected actions of the figure, therefore, due to the construction used here, or its equivalent, make it of continued interest because of the unknown variety of 130

movements which it is capable of producing.

While the shaft 8 is continuously rotated by the pinion 13, yet the gears 9, 10 and 5 their teeth 15, 16 are free to rotate thereon or therewith as the case may be, as is clear.

An important operation, also, is the following: As the cam-wheel 6 rotates, it not 10 only shifts the member 14 to change the relation of the leg movement, but likewise moves the arms 29.

That is to say, said cam-wheel moves the bell-crank 32 back and forth and as the 15 said arms rest against the ends of the rod 30, one of them is raised and the other lowered in each rotation of said cam-wheel and this may be so timed that as the change in leg action occurs a change in the arm 20 position is likewise affected. And since the dress-skirt of the figure is attached to each hand of the figure, it will be lifted and lowered in accordance with such arm movement. This results in a very lifelike action, 25 or as of a person actually dancing.

Slight changes may, of course, be made in the manner of producing the effects herein described without sacrificing the spirit of the invention or departing from the scope 30 of the appended claims.

What is claimed is:

1. In a dancing figure including a body and legs pivoted thereto, in combination, a source of power mounted in the body, a 35 drive wheel operated thereby, separate operating means connected with each leg including a slidable clutch-portion, a driving clutch-member disposed between the clutch- portions continuously rotated by the power 40 source, and means operated by the said power source adapted to shift the clutch-member alternately into and out of engagement with said clutch-portions.

2. In a dancing figure including its body 45 and legs pivoted independently thereon, in combination, power mechanism mounted in said body including a driving member, a clutch operated by the driving member, separate means operatively connected to each 50 leg for moving each independently of the other and means for automatically moving the clutch into engagement with either of the said means.

3. In a dancing figure, in combination 55 with a body thereof, legs pivoted thereto adapted for movement independently of one another and one adapted for movement while the other is stationary, power mechanism including a driving member, separate 60 leg-operating means separately connected to each leg, a clutch member rotated by the driving member, and means to automatically shift the clutch from one leg-operating means to the other.

4. In a dancing figure, in combination 65

with the body thereof, a pair of supporting legs pivoted thereto adapted to swing independently of one another in a sidewise direction, power mechanism mounted on said body including a driving member, a clutch 70 in permanent driven relation with said member, two separate and independent means interposed between the clutch and said legs each connected independently with one of said legs and separately engaged by the 75 clutch adapted to separately impart movement first to one leg and then to the other, and means to automatically shift the clutch.

5. In a dancing figure, in combination 80 with the body thereof, a pair of supporting legs pivoted thereto adapted to swing independently of one another in the direction of one another, power mechanism, a clutch permanently connected with the power, means to shift the clutch in two 85 directions automatically, and separate means independently connected with each leg adapted to be separately engaged by the clutch to impart movement separately to said legs. 90

6. In a dancing figure, in combination 95 with the body thereof, a pair of supporting legs pivoted thereto adapted to swing independently of one another in the direction of one another, power mechanism, a clutch permanently connected with the power, means to shift the clutch in either of two directions automatically, and separate means independently connected with each leg adapted to be separately engaged by the clutch to 100 impart movement separately or jointly to said legs.

7. In a dancing figure, in combination, power mechanism mounted in the body thereof, a pair of legs pivoted on said body 105 adapted for vibratory movement in the same plane, a clutch rotated by the power mechanism, means to automatically shift the clutch axially in opposite directions, separate means independently connected with each leg with either of which the clutch is adapted to separately or intermittently engage whereby to impart movement to one of said legs independently of the other. 110

8. In a dancing figure, in combination, power mechanism mounted in the body, a pair of legs pivotally attached to the body adapted to vibrate in the same plane, a clutch rotated by the power mechanism, means to automatically shift the clutch, separate means connected to each leg, each including a clutch portion to receive said clutch, the relation of parts being such that in the movement of the clutch, but one of the legs will be operated followed by the 120 operation of both, and then the independent operation of the other leg of said legs. 125

9. A dancing figure including a pair of legs pivoted to the body thereof adapted for independent movement in one plane, sep- 130

- arate means permanently connected with one leg independent of the other, power mechanism including an automatically shiftable clutch adapted to engage but one 5 of the said means, or both together, whereby either one or the other of the legs is independently vibrated on its pivot and whereby also, both legs will be vibrated at the same time.
10. 10. A dancing figure including a pair of legs pivoted to the body thereof adapted for independent movement in one plane, separate means permanently connected with one leg independent of the other, power 15 mechanism including an automatically shiftable clutch adapted, while having engagement with one of said means to be shifted into engagement with the other and operate both at the same time, and then 20 to release the first named leg and operate the second only.
11. A dancing figure including power mechanism, a pair of legs independently pivoted on the body adapted to move in one 25 plane, arms also pivoted on said body adapted for movement in the same direction as the legs, means operated by said mechanism to operate the legs both simultaneously and independently, and means to operate the 30 arms in a different time from that of the legs.
12. A dancing figure including a body, and legs and arms pivoted thereto to move in one plane, power mechanism mounted 35 in the body including means to vibrate the legs independently or both at the same time comprising two pairs of pinions, each pair being independently connected operatively to one of the legs, two gears each meshing 40 with one of the pairs of pinions, power means, a clutch driven thereby, and means to shift the clutch into driving engagement with one or the other of the said two gears to terminate the movement of one of the 45 legs and impart movement to the other, and means to raise one arm and lower the other operated by the first said means as the
- change of drive from one leg to the other occurs.
13. A dancing figure including a body 50 and legs independently pivoted thereto adapted to swing in parallel planes, arms also pivoted independently on the body adapted for movement in parallel planes and parallel to the planes of movement of 55 the legs, means for operating the legs independently of one another including clutch portions, a power source including a slide- able clutch member operated thereby, power operated means for moving the clutch member into engagement with either of the operating means of the said legs, and a re- ciprocating rod operated by the said power operated means adapted to move the arms in a different timing from the legs. 65
14. In a dancing figure, in combination with a body and arms and legs separately and independently pivoted thereto, a power source in said body, separate and in- dependent means adapted when operated to 70 separately vibrate the legs and each includ- ing a rotatable part and a pitman connect- ing it with a leg, a separate clutch-portion operatively connected to each of the rotat- able parts, a slideable clutch-member lying 75 between the clutch-portions adapted to be continuously operated by the power source, means to shift the member alternately from one to the other of the clutch-portions, said clutch-member in the direction of its slide- 80 ing movement being greater in measure- ment than the distance between said clutch- portions whereby during the shifting move- ment from one clutch-portion to the other both legs will receive motion, and means 85 operated by the shifting means to alter- nately lower one of the arms and raise the other.

In testimony whereof I affix my signature in presence of two witnesses.

ERNEST STARBUCK.
